UNITED STATES PATENT OFFICE

AUGUST KRASTIN, OF CLEVELAND, OHIO

ELECTRIC SWITCH

Application filed April 4, 1928. Serial No. 267,177.

This invention relates to electric circuit control switches. The general object is to provide a switch which may be economically manufactured from a small number of parts, 5 and which will be certain in operation, both to open and close an electric circuit. A specific object is to provide a simple effective device in connection with an operating arm of an electric switch, for insuring certainty 10 of the arm. A further object is to provide a simple device for preventing displacement of the operating arm return spring.

Further objects and features of the invention will become apparent from the following description relating to the accompanying drawings, wherein I have shown my preferred form. The essential characteristics 15 will be summarized in the claims.

In the drawing, Fig. 1 is a plan view of 20 the present embodiment of the invention; Figs. 2 and 3 are longitudinal cross sectional views taken along the lines 2—2 and 3—3 on Fig. 1 respectively; and Fig. 4 is a fragmentary detail view of the switch operating arm 25 and support thereof.

The switch, as shown, includes a casing 1, adapted to be mounted on any suitable support and arranged to contain a pair of strip spring contacts 10. The contacts are placed 30 parallel to each other and in a common plane, and are arranged to be electrically connected by a metal bar 18 carried on an arm 15 and electrically insulated therefrom, the arm being pivotally mounted upon a cross pin 16 supported in the side walls 5 of the casing. 35

The casing 1 is preferably a single piece shell made up of pressed sheet metal. In the position shown, the casing is entirely open at the top, and it may be assumed that 40 the line A designates a supporting surface whereby, in conjunction with the casing walls, the parts interiorly of the casing are completely housed. The lowermost wall portion of the casing is designated 4. The 45 side walls 5 are contiguous with the portion 4 and are sheared out of the sheetmetal blank in the contour shown in Fig. 2, and bent up to lie parallel with each other, as shown in Fig. 1, their end marginal edges abutting 50 upwardly extending end wall portions 6 and

7 also contiguous with the wall portion 4. The side walls have ears or brackets 8 turned outwardly therefrom, as shown in Fig. 1, by which the casing may be supported, as by screws (not shown) inserted through openings 8' in the ears. The side wall portions 5 of the casing are held in position by riveting over the ends of the pin 16 as at 16'.

The spring contacts 10 are supported on one of the end wall portions 6 as shown particularly in Fig. 3, wherein are shown a pair of insulating strips 11, one on each side of this wall portion 6. The attached ends of the strips 10 overlie the innermost insulating strip 11 and may be secured in place by individual rivets 12 internally threaded for the reception of respective binder screws 13 for holding the conductor wires in place. One of such wires is shown at 14. The free ends of the strips 10 are doubled to form the contact surfaces 10' over which the contact bar 18, previously mentioned, moves with a wiping action. The operating position of the bar 18 for closing the circuit is illustrated in Fig. 3.

For returning the arm 15 to its normal position after each actuation, I employ a wire spring 19 which is substantially bi-symmetrical relative to the plane of movement of the arm, the spring having a central stretch 20 bearing against one edge of the arm, and contiguous coils 21 surrounding the pin 16, the ends 22 of the spring being retained beneath lugs 23 upstruck from the side walls 5 of the casing.

One of the novel features of the present invention is the device which I use for preventing the arm 15 from displacement along the pin 16. This device comprises undercutting the pin 16 as at 17 and providing an opening 26 in the arm large enough to slip over one end of the pin. The peripheral edges of the opening are retained in position in the undercut 17 by reason of the reaction of the spring which forces the upper end of the arm to the right as shown in Fig. 2, holding the opening in eccentric relation to the pin. The free end of the arm is guided in a slot 27 in the bottom wall 4 of the housing. The particular advantage

of the above device is that while it does not materially increase the manufacturing cost, or the cost of assembly, it insures the bar 18 making even contact with both surfaces.

5 In Fig. 4 I have shown the undercut portion 17 of the pin 16 beveled as at 17; the result of this being that in case the arm has a tendency to ride up out of the undercut, it will be cammed down onto the smaller diameter by the beveled surfaces.

10 A further refinement of the switch is that the intermediate portion 20 of the spring is retained against movement along the edge of the arm 15. The refinement consists simply 15 in placing shallow notches 28 on opposite edges of the arm 15. The reason for the plurality of notches is that this makes it unnecessary for the workmen, when assembling the switch to take notice which edge of the 20 arm is toward the spring.

I claim:

1. In an electric switch, a casing, a pin carried thereby having a reduced portion intermediately of its ends, an arm pivotally mounted upon the pin and having a through opening loosely fitting the pin at the reduced portion, electric conductive means carried by the arm and electrically insulated from the arm, and a pair of spring contacts carried by the casing in position to be engaged by said means in one position of the arm.
2. In an electric switch, a casing, a pin carried by the casing and having a peripheral groove intermediately of its ends, an arm having an enlarged opening adapted to embrace the pin at said groove, said arm being adapted to open and close an electric circuit, and resilient means for holding the 40 arm in a definite position, said means reacting on the arm to hold the opening thereof in eccentric relation to said groove, thereby preventing displacement of the arm along the pin.
3. In an electric switch, a casing, a pin carried by the casing and having a peripheral groove intermediately of its ends, an arm having an opening adapted to embrace the pin, the opening being large enough to permit the arm to be assembled on the pin lengthwise thereof, said arm being adapted to make and break an electric circuit, one wall of the casing having a slot embracing the arm for guiding the movement thereof and located in the plane of said groove.
4. In an electric switch, a casing, a pin carried by the casing, an arm pivotally carried by the pin and adapted to open and close an electric circuit, said pin having a peripheral groove, and the arm having an opening embracing the pin at said groove but large enough to enable the arm to be moved for a considerable distance along the pin, spring means arranged to act on the 65 arm to hold it in a definite position, said

spring means also acting on the arm to hold the opening thereof in eccentric relation to the pin, whereby the attached end of the arm is normally prevented from moving along the pin.

5. An electric switch comprising in combination, a casing, a pin carried by the casing and extending therethrough, an arm pivotally carried on the pin, and adapted to make and break an electric circuit when moved to two different positions, there being a coil spring surrounding the pin at each side of the arm and having a portion thereof connecting the coils and bearing against one edge of the arm to maintain the arm in a definite position, relative to the casing, said arm having a notch adapted to receive said connecting portion of the spring, whereby said connecting portion is prevented from displacement along the arm.

In testimony whereof, I hereunto affix my signature.

AUGUST KRASTIN.
